SCREW LOCKING MEANS

Martin H. Redmer, Chicago, Ill.

Application February 29, 1936, Serial No. 66,369

3 Claims. (Cl. 151—32)

My invention relates to screws.

More particularly, my invention relates to an improved type of head for a screw whereby the screw may be threaded more readily into place without destroying the head by failure of the wrench or screw driver to align properly or to be fitted in the head.

As manufactured today, the type of screw known as the socket screw, which is usually countersunk in the parts into which it is threaded, is generally provided with an octagonal recess in its head to receive a key wrench. The octagonal shape of the recess provides surfaces between the recess and the key wrench which do not oppose the turning effort as efficiently as a surface extending substantially radially outwardly so as to be practically transverse to the turning effort. Consequently, a key wrench must fit the recess with considerable accuracy to prevent destruction of the recess by the sharp corners of the wrench. Moreover, an octagonal recess requires removal of material from that part of the head which considerably weakens the head. As the screw is driven into position and the head is countersunk, an octagonal recess provides no means for locking the screw in place to prevent it from accidentally becoming loose.

An object of my invention is to provide, therefore, an improved type of recess in the head of a screw, which recess is preferably in the form of opposed sectors open at the edges of the head.

A further object of my invention is to provide a recess in the head of a screw of the kind described, which does not weaken the construction of the head, and which further provides for engaging surfaces between the head and the key wrench that are in the most efficient position to transmit the turning force. Accordingly, the screw may be threaded into position and tightened with minimum turning effort and without the danger of destroying the head.

A further object of my invention is to provide an improved type of recess in the head of a screw that may receive a key or like locking member after the screw is tightly driven into position, which will prevent the screw from vibrating or otherwise working loose.

According to the present invention I further contemplate providing a novel key or locking device that may be inserted into a recess of a screw head and locked therein in a manner to bind against the part into which the screw is countersunk and thereby lock the screw in position.

In this connection, it is a still further object of the invention to provide a locking device of this

type which can be readily placed in the recess in the screw head and, by slight tapping, caused to wedge itself against the walls of the recess and the part receiving the screw—the construction of the locking device permitting, not only of simple use and low cost of manufacture, but also of ready removal in case it is desired to withdraw the screw.

Further objects of my invention will be apparent from the following detailed description taken in connection with the accompanying drawing.

In the drawing:

Figure 1 is a perspective view of a screw having a recess in its head of the type embodying the present invention;

Fig. 2 is a plan view of the screw head;

Fig. 3 illustrates the type of key wrench that may be used;

Fig. 4 is a view of the end of the key wrench that fits into the recess in the head of the screw;

Fig. 5 is an edge view of a key or locking device adapted to be inserted in the recess of the screw head;

Fig. 6 is a plan view of this key or locking device;

Fig. 7 is a sectional view illustrating the screw driven into position and the head of the screw countersunk so as to show the manner in which this key or locking device prevents the screw from vibrating or otherwise working loose; and

Fig. 8 is a perspective view illustrating the manner in which a tool may be used to remove this key or locking device when it is desired to remove this screw.

Referring now to the drawing, Fig. 1 illustrates a screw having a threaded shank 1 and a head 2. Opposed sector-like recesses are provided in the upper part of screw head 2. These opposed sector recesses are designated 3 and 4 and are joined at the center of the head, as indicated at 5, in a somewhat restricted manner due to this sector formation, the center portion 5 being of such width as to permit insertion of a key wrench of corresponding shape. It is noted that sector recesses 3 and 4 extend outwardly to and are open at the edges 6 and 7 respectively of screw head 2. Recesses 3 and 4 provide walls 8 and 9 acting as engaging surfaces for the key wrench and being substantially radial so as to be somewhat transverse to the turning effort.

In the manufacture of the screw head 2, walls 8 and 9 are cut at an angle to require but two milling operations in the formation of recesses 3 and 4. Although I do not necessarily wish to be limited to an exact angle of cut for walls 8

and 9, I have found that by setting the milling cutters at 15° with respect to the horizontal, only two cutting operations are required to form these recesses 3 and 4. After the first cutting operation, the milling cutter may be indexed so that an opposite cut at 15° may be performed to form the opposite walls. No material is then left in the center of the recesses at the edges 6 and 7. One of the advantages, therefore, of cutting recesses 3 and 4 outwardly to the edges 6 and 7 resides in the simplicity of operation and inexpensive cost of production. Walls 8 and 9 remain in an angular position sufficient to be somewhat transverse to the turning movement, and therefore, in the most efficient position when the key wrench is inserted to operate to thread the screw into locking position or to remove the same from locked position. Screws of this type are quite frequently used as keys to lock rotating parts together, such as is shown in Fig. 7. This requires that the screw be driven into position as tightly as possible so that there is no opportunity for slippage between the rotating parts. Moreover, it is essential that the screw remain locked to keep these operating parts keyed together. The formation of recesses 3 and 4 advantageously permit the use of a key-lock shown in Figs. 5 and 6. This key-lock, designated 12, is of substantially the same cross section as recesses 3 and 4, but may be slightly curved so that when key-lock 12 is inserted in these recesses it may be tapped slightly to cause distortion and a wedging action with the walls 8 and 9 and the side wall of the part in which head 2 is countersunk. For example, in Fig. 7 I have illustrated, say, a driving shaft 13 and a driven shaft 14. The screw is used as a key to lock parts 13 and 14 in driven relation. Head 2 is countersunk as is usual in these cases. Countersunk screws of this type may have an enlarged head 2, as shown in Fig. 1 of the drawing. It may also have a head of the same diameter as shank 1, as is well understood and commonly used in the art. Irrespective of whether head 2 is enlarged, it will be noted that the arcuate edges 15 at each side of key-lock 12 will bind against wall 16 of the countersunk recesses in part 15. Key-lock 12 may be made of relatively soft material which will permit it to spread when tapped or pounded into recesses 3 and 4.

If key-lock 12 is made of relatively soft material it may be removed without difficulty. I suggest providing an opening 17 in the center 5 where the material is constricted to conform to the center 5 where recesses 3 and 4 are joined as previously explained. Hole 17 enables the placing of a punch 18 against key-lock 12 so that it may be readily split or torn apart, starting at the center where hole 17 is, when it is desired to remove key-lock 12 from the head 2. Any sharp instrument may be used instead of punch 18, or any means may be provided to initiate the quick removal of key-lock 12 from recesses 3 and 4. On the other hand, it may not be necessary to provide hole 17 to act as a means of starting the splitting or tearing action of the key-lock at the center to enable removal of the sectors.

70 It will be noted that key-lock 12 provides a very simple and inexpensive key to lock the screw

in position and effectively to prevent vibration loosening or permitting the screw to work loose. The arcuate edges 15 of this key-lock effectively grip the wall 16 when this key-lock is inserted in the recesses. Furthermore, key-lock 12 is 5 permanent in its action and will remain in the recesses of head 2 until forcibly removed by means of a punch 18 or other sharp instrument.

Any type of key wrench such as I have designated 20 and illustrated in Figs. 3 and 4 may be 10 used to operate the screw. The lower end may be cut so that it will conform to the size and shape of recesses 3 and 4. This lower end 21 will then act as a key that will readily fit in these recesses in head 2 and securely engage 15 walls 8 and 9 to drive the screw into position, permitting the turning effort to be efficiently transmitted without imposing too great a strain on head 2. Cutting recesses 13 and 14 in a 20 manner to form opposite walls 7 and 8 at a relatively small angle, such for instance as 15°, not only minimizes the cutting operations but likewise leaves a maximum amount of material in the segments 22 and 23 to prevent destruction of the head by the key wrench. Moreover, it 25 provides recesses of such conformation as to enable key wrench 20 to be readily inserted in the recesses although the screw may be located at an inconvenient point to the mechanic.

Without further elaboration, the foregoing will 30 so fully explain the gist of my invention that others may, by applying current knowledge, readily adopt the same for use under varying conditions of service, without eliminating certain features, which may properly be said to 35 constitute the essential items of novelty involved, which items are intended to be defined and secured to me by the following claims.

I claim:

1. A screw comprising a head and a threaded 40 shank, said head having substantially flat recesses which join at the center of the head, each recess being substantially a sector extending to the periphery of the head to provide an open end, and a locking member of substantially the same 45 cross section as that of said recesses adapted to be inserted therein and wedged against their walls and the wall of the member into which said screw is threaded to lock said screw in position.

2. A screw comprising a threaded shank and 50 a head having a substantially flat recess therein, said recess being open at the edge of said head, and a locking member of substantially the same cross section as that of said recesses and wedged 55 thereinto in binding relation with the walls of said recess and the wall of the part in which said head is countersunk.

3. A screw to be countersunk in a work piece comprising a head and a threaded shank, said head having substantially flat diametrically opposed recesses joining each other in the center, said recesses being defined by side walls extending through the periphery of the head to provide an open end for each recess, and an initially arcuate locking member flattened into said recesses in binding relation with the walls thereof and through the open end in binding relation with the wall of the work in which said head is countersunk.

MARTIN H. REDMER.
